United States Patent Office.

JOSEPH S. LEHMAN, OF MOUNT JOY, PENNSYLVANIA.

Letters Patent No. 74,232, dated February 11, 1868.

IMPROVED BAG-HOLDING APPARATUS.

The Schedule referred to in these Letters Patent and making part of the same.

TO ALL WHOM IT MAY CONCERN:

Be it known that I, JOSEPH S. LEHMAN, of Mount Joy, in the county of Lancaster, and State of Pennsylvania, have invented a new and useful Bag-Holding Device and Truck; and I do hereby declare that the following is a full, clear, and exact description of the construction and operation of the same, reference being had to the annexed drawings, making a part of this specification, in which—

Figure 1 is a perspective view.

Figure 2 is a longitudinal elevation.

Figure 3 is a section of flanged or slotted jaws.

Figure 4 is an angular frame.

Figure 5 is a screw-rod.

Figure 6 is a spring.

B B, the flanged or slotted jaws, are placed over the inside of the bars of the truck-frame A A, being held in position by rod D, there being a socket in one of the slotted jaws, with screw-thread through the other, corresponding to the rod, so that the jaws may be adjusted with any degree of tension to the frame of the truck by turning the rod. The dove-tail notches in B B receive the angular frame C through its notches; when pushed past the notches to its centre is firmly held in position; spring E, when riveted to the outer face of the slotted jaws and set with a pressure to work against the frame, holding the jaws at any position they may be placed on the frame of the truck.

What I claim, and desire to secure by Letters Patent, is—

The construction of the flanged or slotted jaws B B, clamping-rod D, and spring E, with the angular frame C, in combination with the truck-frame A, all arranged and operating as and for the purpose herein described.

JOSEPH S. LEHMAN.
